TUMBLING MACHINE

John E. Vеторино, Fairhaven, and Norman R. Gendron, New Bedford, Mass., assignors to Continental Machinery Co., Inc., New Bedford, Mass., a corporation of Massachusetts

Application December 9, 1942, Serial No. 468,445

18 Claims. (Cl. 68—25)

The present invention relates to tumbling machines, and more particularly to machines for tumbling hides, skins, fabrics and the like during degreasing, washing, or otherwise treating the same. The present application is a continuation-in-part of application, Serial No. 365,366, filed November 12, 1940.

In Letters Patent 1,979,237, issued October 30, 1934, to Frank Vеторино, there is disclosed a unitary laundry machine for both washing the laundry and then drying it. The machine comprises a plurality of wash-containing combination tumbler-and-extractor perforated drums or cylinders removably and interchangeably mounted, with their axes horizontal, in individual washing tubs containing washing fluids. The tubs are mounted upon a frame symmetrically with respect to a vertically disposed shaft that is rotatable by a motor under the control of a positively operating clutch.

In operation, the tubs are filled with washing fluids, and the cylinders are loaded with clothes to be laundered. With the clutch ineffective, the frame that carries the tubs being at this time held stationary by a brake, the motor automatically rotates the cylinders in their respective tubs about their horizontal axes, first in one direction, and then in the opposite direction, alternately. This results in tumbling the clothes in the washing fluids to effect the washing operation.

After the washing cycle has been completed, and while the cylinders are still rotating, the tubs are drained of the washing fluids; whereupon the brake is released and the clutch is simultaneously rendered effective to rotate the vertically disposed shaft from the same motor. The frame, the tubs mounted thereon, and the cylinders contained in the tubs become thus revolved as a unit with the vertically disposed shaft about the axis thereof to extract by centrifugal action the washing fluids still remaining in the laundry after the draining.

Because the application of the clutch, at the commencement of the extracting cycle, is quite sudden, notwithstanding that it slips frictionally to some extent, there is a tendency for the rotation of the cylinders about their horizontal axes to become stopped dead short immediately upon the commencement of their revolution about the vertical axis. This sudden transition, coupled with the fact that the machine is quite heavy, introduces considerable shock and jar.

The machine was therefore re-designed in order to reduce this shock and jar. According to the

operation of the re-designed machine, disclosed in Patent 2,235,467, issued March 18, 1941, to the said Frank Vеторино and John E. and Joseph E. Vеторино, the load was reduced by eliminating the frame that carried the rotatable tubs, and by mounting the combination tumbler-and-extractor cylinders permanently at opposite ends of a horizontally disposed carrier shaft. The positively driven clutch of the machine of Patent 1,979,237, moreover, was replaced by a centrifugally acting clutch that did not become effective immediately upon the release of the brake. The centrifugally acting clutch comprised a plurality of clutch shoes that were forced by centrifugal action into engagement with a rotating clutch flange. One reason for the adoption of the centrifugal clutch was that the re-design of the machine required the re-location of certain intermeshing bevel gears of the original machine, and this re-location, it was thought, would interfere with the drive of a positively acting clutch.

In this re-designed machine, the rotation by the motor of the cylinders about the axis of their horizontally disposed carrier shaft was continued for a brief period of time after the release of the brake. During this brief time period, when neither the brake nor the clutch was effective, not only did the motor continue to rotate the cylinders about their common horizontal axis, but it also commenced to revolve the cylinders with their carrier shaft as a unit about the axis of the vertically disposed shaft. A combined rotation of the cylinders about their horizontal axis and revolution about their vertical axis was thus introduced. The revolution about the vertical axis was at first slow, but later at gradually increasing speed. The rotation of the cylinders about their horizontal axis gradually decreased, furthermore, as their revolution about the vertical axis increased. When the clutch finally became effective, upon the machine attaining sufficient speed of revolution about the vertical axis, therefore, it was with considerably less shock and jar than was the case with the machine of Patent 1,979,237.

Once this speed of revolution was arrived at, it was expected that the clutch would remain effective to revolve the cylinders about the vertical axis, and without any further rotation of the cylinders about their horizontal axis. This expectation was not, however, fully realized, in practice.

One objection to the re-designed machine is that, in effect, it is idle a large part of the time;

for the intervals required for the machine to pick up sufficient speed of revolution about the vertical axis to throw out the clutch shoes by centrifugal action turned out to be rather long. There is nothing definite, positive, determinate or dependable, furthermore, in this rather long time of delay; it may be great or small, depending upon the load and other conditions of operation. One is never certain, indeed, as to whether, unless sufficiently heavy loads, the centrifugally acting clutch shoes will really take effect at all, at any time. Under many conditions, these clutch shoes no sooner engage the rotating clutch flange than they let go again, over and over again; thus successively rubbing gently against the clutch flange and then disengaging it, a number of times, but without ever obtaining frictional grip sufficiently permanent to pick up the load required during the extracting cycle.

Under such conditions, therefore, the theoretically expected cessation of the rotation of the cylinders about their horizontal axis does not take place, even after the clutch shoes do begin lightly to engage the clutch flange. All that is attained is merely a continuation of the same combined rotation of the cylinders about their horizontal axis and revolution about the vertical axis that obtained before the clutch shoes began to engage and disengage the clutch flange. Pure vertical revolution only of the cylinders, without their accompanying horizontal rotation, is seldom attained.

An object of the present invention is to provide a new and improved unitary machine of the character disclosed in the said Letters Patent for both tumbling the contents of the cylinders in solvent or other liquid, in order to wash, degrease or otherwise treat the contents, and then drying the same.

Another object is to transfer, at will, positively, at any speed of operation of the machine, and at any desired time, but without shock or jar, from a pure rotation of the cylinders about their horizontally disposed axis to a pure revolution of the cylinders about the vertically disposed axis.

A further object is positively to control the length of the time period that shall elapse between the moment when the cylinders commence revolving about the vertically disposed axis and the movement when they cease rotating about their horizontally disposed axis.

Other and further objects will be described hereinafter and will be particularly pointed out in the appended claims.

With the above ends in view, a machine has been devised of a nature similar to that of the said Letters Patent, but in which the time when the clutch becomes effective, in order to reduce shock and jar, may be controlled either automatically, or manually, or both, as circumstances may require. According to a feature embodied in the preferred machine that is illustrated and described herein, this time may be controlled by providing for a time sequence of operation of the brake and the clutch, or by a suitable adjustment of the clutch slip, so as to permit slippage to a predetermined degree, or both.

The invention will now be more fully described in connection with the accompanying drawings, in which Fig. 1 is an end elevation of a machine embodying the present invention, in preferred form, parts being broken away and other parts being shown in transverse vertical section, for clearness; Fig. 2 is a horizontal section taken

upon the line 2—2 of Fig. 5, looking downward, in the direction of the arrows; Fig. 3 is a side elevation similar to Fig. 1, partly in longitudinal vertical section upon the line 3—3 of Fig. 1, 5 looking in the direction of the arrows; Fig. 4 is a fragmentary plan, with upper parts of the machine removed, showing the supporting annulus for the brake-disengaging member and related parts; Fig. 5 is a fragmentary side elevation similar to Fig. 3, but upon a larger scale, and showing in section many parts shown in elevation in Fig. 3; Fig. 6 is a section upon a larger scale, of parts shown in Fig. 5; and Figs. 7 and 8 are sections taken upon the lines 7—7 and 8—8, 10 respectively, of Fig. 6, looking in the directions of the arrows.

The illustrated form of the present invention comprises an upright outer stationary cylindrical frame or casing 1 that may constitute a cleaning-and-drying or washing-and-drying or degreasing-and-drying chamber or the like. A pair of angle-iron reinforcing bands 2 and 3 are shown suitably secured to the casing 1 around its upper and lower ends, respectively. The upper end of the casing 1 is surmounted by a circularly formed dome-shaped covering top 7, provided around its lower edge with an angle-iron reinforcing band 8, shown bolted at 87 to the flange 2. A circular cap-like clutch housing 31 15 is secured to the upper surface of the cover 7 by means of bolts 33 extending through a bottom edge flange 32.

An outwardly opening circular door 11 is hinged at 12 to the casing 1. The door 11 closes 20 on an annular flange 13 that surrounds a circular-door opening 14 provided in the casing 1. A pair of keeper bolts 15, hinged at 88 to the flange 13, 25 may be swung into bifurcated edge lugs 16 on the door 11 to force the door 11 tight 30 to the flange 13.

Within the casing 1, at opposite sides thereof, there are disposed inner combined tumbler-and-extractor drums or cylinders 17, each provided with concavo-convex, oppositely disposed, front and back side or end walls 18 and 19. The back end walls 19 are shown arching inwardly and the front walls 18 outwardly. With the exception of the back walls 19, the cylinders 17 are shown perforated at 24. The cylinders 17 are detachably secured together coaxially, in back-to-back spaced-apart relation, at the respective ends 21 of a short horizontal transversely disposed shaft 20, that is positioned intermediate between the cylinders. By reason of this construction, each cylinder acts as a counterweight, to counter-balance the other on the shaft 20. The shaft 20 is tapered at its ends 21 to fit into axial sockets 22 provided on the inwardly arching back walls 19. The cylinders 17 are clamped to the ends of the shaft 20 in any suitable manner, as by means of bolts 23 that pass through the back walls 19 of the respective cylinders and into the shaft 20. Each cylinder 17 is thus carried by the shaft 20 at its inner end wall 19.

Each cylinder 17 is provided with an annular door frame 25 that is suitably secured concentrically in the front wall 18 of the cylinder. Each cylinder 17 is provided also with a perforated circular door 27, preferably arched inwardly of the cylinder, and fitted within the door frame 25. The door 27 may be detachably secured in the frame 25 by means of an edge lug 28, that fits in a grooved inner edge 26 of the frame 25, and a pair of latch bolts 29. The bolts 29 are

suitably mounted on the outer face of the door 27, so as to be projected into the grooved edge 26 under the urge of springs 30.

The doors 27 are slightly smaller than the door-frame openings 14, to enable their being removed therethrough. It is through these doors that, as hereinafter more fully described, the open-ended cylinders 17 are loaded and unloaded with hides, skins, laundry and the like.

The cylinders may be rotated about the axis of their horizontally disposed shaft 20, to tumble their contents, thereby to effect a washing, cleaning, degreasing or other operation. They may also be revolved as a unit about the vertical axis of the casing 1, to extract liquid from the tumbled contents by centrifugal action. This vertical axis, though between the cylinders 17, is disposed externally of each cylinder individually, near the inner end wall 19 thereof.

The drive for effecting either or both of these actions is obtained from a pulley 34, shown driven continuously from an electric motor 41, through the medium of a belt 44. The pulley 34 is horizontally disposed concentrically in the upper portion of the housing 31, and is rotatable axially of the casing 1 and the housing 31 on a bolt-like arbor 38. The arbor 38, extended through the top of the housing 31, is fixed on the upper end thereof by a nut 39 that is covered by a cap 40, suitably fixed to the housing 31.

The pulley 34 is provided with a depending circumferential skirt that constitutes a clutch flange 35. A bevel gear 36, disposed within the pulley 34, is provided with a hub that is keyed, as shown at 37, in the hub of the pulley 34. The bevel gear 36 is thus rotated from the pulley 34.

The electric motor 41 is shown bolted at 42 to a bracket 9 that extends from one side of the cover 1. The belt 44 extends through a suitable throat 79, provided in the same side of the housing 31, over the pulley 34 and a pulley 45 that is fast on the uprightly disposed armature shaft 43 of the motor 41. The belt 44 is shown as of the multiple-band type, and the pulleys 34 and 45 are grooved suitably to receive this type of belt.

A flat hollow carrier gear casing 46 is upwardly disposed, centrally of the shaft 20, for revolution within, and about the said vertical axis of, the casing 1. The cylinder-carrying shaft 20 is journaled in, and extends through, ball-bearing assemblies 55. The ball-bearing assemblies 55 are suitably fitted and secured in annular flanges 86 of the sides of the gear casing 46. The tapered ends 21 of the shaft 20 extend beyond the bearings 55 in which the shaft 20 is journaled. The gear casing 46, therefore, functions as a carrier for the cylinder-carrying shaft 20, with the cylinders 17 disposed on opposite sides of the carrier 46.

The shaft 20 is thus not only rotatable about its own axis, but it is also revolvable, in unison with the gear casing 46 in which it is mounted, and the cylinders 17 carried thereby, about the said vertical axis of the casing 1.

The lower end of the gear casing 46, as shown more particularly in Fig. 5, is provided with a step-shaped trunnion 48 that extends through a suitable stuffing box 49, so as to be supported or journaled in a suitable end-thrust bearing-assembly 51. The stuffing box 49 is bolted at 50 in a centrally disposed opening or aperture 6 of a bottom wall 4 of the casing 1, that is shown reinforced by radial flanges 5, and the bearing-

assembly 51 is bolted at 52 to and beneath this bottom wall 4.

The upper end of the gear casing 46 is provided with a tubular neck 92 that, as shown more particularly in Fig. 6, extends upward through a centrally disposed aperture 90 in the upper wall 99 of the cover 1, and through a ball-bearing assembly 89 contained in a tubular housing 53, into the lower portion of the housing 31. The housing 53, with the ball-bearing assembly 89 therein, is shown held to the cover 1 by bolts 54 that extend through a flange 98 of the housing 53, into the upper wall 99 of the cover 1. A skirt 102, depending from a circular flange-like or disc-like brake plate 47, rests on the upper surface of the housing 53.

A wall 100, welded in place to close the upper end of the neck 92, is provided with a keyway 101, shown more clearly in Fig. 8. The depending skirt 102 is provided with a cooperating keyway 103. A key 104, disposed in the key-ways 101 and 103, and bolts 105, extending through the skirt 102 and the wall 100, hold the gear casing 46 fixed to the brake plate 47.

The brake plate 47 is thus concentrically fixed in the lower portion of the housing 31 at the upper end of the gear casing 46. The upper surface of the plate 47 carries an annular brake disc 138 for holding the gear casing 46 against revolution about the vertical axis. The position of the brake disc 138 upon the plate 47 may be adjusted by means of bolts 139.

An annular bushing or sleeve 123 and lugs 119 stand up fixedly from the brake plate 47 in the housing 31 below the pulley 34. The axis of the bushing 123 coincides with the vertical axis of the housing 1; it is therefore concentric with the brake disc 138. A transversely disposed cross-shaft 69 extends horizontally through, and is fixed in the upper ends of, the lugs 119, inside the clutch flange 35.

A pair of segmental-shaped clutch shoes 70 are slidably mounted on opposite ends of the shaft 69, between the clutch shoes 70 and the lugs 119. The clutch shoes 70 are thus fixed to the cylinders 17 to communicate their revolution thereto.

Light normally ineffective coil springs 71 are sleeved on the respective opposite ends of the shaft 69, between the clutch shoes 70 and the lugs 119. The springs 71 tend yielding to actuate the clutch shoes 70 outwardly to actuate their outer faces into cooperating clutching engagement with the inner face of the rotatable clutch flange 35, as illustrated more particularly in Fig. 5. During such clutching engagement, the clutch shoes 70 rotate with the rotatable clutch flange 35. The clutch flange 35 thus constitutes the continuously driven rotatable clutch member and the clutch shoes 70 the cooperating clutch member of the clutch. The clutch is effective to revolve the cylinders 17 as a unit about the vertical axis when the clutch shoes 70 engage the clutch flange 35.

In the normal position of the clutch shoes 70, in which the clutch is normally ineffective, the clutch shoes 70 are released from clutching engagement with the clutch flange 35. The clutch shoes 70 may be released from clutching engagement with the clutch flange 35 by sliding them inwardly on the shaft 69, as hereinafter described.

A small sprocket wheel 73 is mounted on, so as to rotate with, the shaft 69, and is confined against lateral movement between the lugs 119. A bevel gear 75, that is fast on the hub of the sprocket wheel 73, meshes with the bevel gear

36, so as to be driven thereby. A large sprocket driving gear wheel 76, centrally mounted within the gear casing 46 upon the shaft 20, between the ball-bearing assemblies 55 and between the cylinders 17, is driven from the sprocket wheel 73 by means of a sprocket chain 77. The sprocket chain 77 passes downwardly, out of the casing 31, into the casing 1, through the housing 53. It passes not only over the sprocket wheels 73 and 76, but also, as shown more particularly in Fig. 1, over a pair of opposed idler sprocket wheels 78 that are suitably mounted in the gear casing 46, upon opposite sides of and adjacent to the neck 92 of the gear casing 46.

The shaft 21, upon which the cylinders 17 are mounted, is thus rotated from the pulley 34 that carries the driven clutch member 35, at a time when the clutch is ineffective, by means of a planetary gear drive comprising the gears 36 and 75, the sprocket wheel 73 driven thereby, the sprocket chain 77 and the sprocket wheel 76. The drive is at this time, not from the driven clutch member 35, but rather from the bevel gear 36, both of which are rotated from the continuously rotated pulley 34 by the motor 41.

An important function of the bushing or sleeve 123 is to centralize an annular brake-disengaging member 127 and a supporting annulus 133 therefor along the vertical axis of the casing 1. The brake-disengaging member 127 concentrically encircles the upper portion of the bushing 123, above the supporting annulus 133 and below the shaft 69 and the clutch shoes 70 mounted thereon. The supporting annulus 133 concentrically surrounds the lower portion of the bushing 123, between the plate 47 and the brake-disengaging member 127.

As illustrated more particularly in Fig. 5, the brake-disengaging member 127 is provided on its inner peripheral edge with an internally beveled upstanding annular flange 129. Anti-friction ball members 132 are carried at the outer ends of studs 130 that extend outwardly from hubs 131 of the clutch shoes 70. The flange 129 and the studs 130 constitute coacting camming devices.

The annulus 133 is rendered resiliently movable, to yield vertically up and down, to a small extent, by mounting it upon a plurality of tempered resilient spring-metal supporting pins 134, that extend radially outward of the annulus 133, into tapered plugs 135. The tapered plugs are threaded on the outer ends of the pins 134, to render them slidably adjustable radially on these pins in the housing 31. The pins 134 prevent the annulus 133 and the brake-disengaging member 127 from rotating with the plate 47.

Both the annulus 133 and the brake-disengaging member 127 are serrated. On its upper base, the annulus 133 is provided with cam notches 137 that are adapted to engage coacting cam lugs 136 upon the lower face of the annular brake-disengaging member 127.

The brake-disengaging member 127 is movable back and forth, through a small angular extent, about the axis of the bushing 123, by means of a hand lever 128 that extends radially outward of the brake-disengaging member 127 through a slot 126 in the clutch housing 31.

When the hand lever 128 is manually actuated clockwise, from the full-line toward the normal dotted-line position of Fig. 2, the brake-disengaging member 127 is likewise actuated clockwise to a corresponding angular extent. By reason of the engagement between the coacting cam

lugs 136 and cam notches 137, the brake-disengaging member 127 is at the same time, however, yieldingly carried upward, as viewed in Figs. 3 and 5, to a small extent, on the cam notches 137.

The brake-disengaging member is thus operable in two directions; angularly, and by a vertical movement of translation. The movement of translation, moreover, automatically accompanies the angular movement, by reason of the coaction of the cam lugs 136 and the cam notches 137.

During the combined clockwise and upward movement of the brake-disengaging member 127, in response to the actuation of the lever 128 from the full-line toward the dotted-line position of Fig. 2, the beveled flange cam 129 will engage the anti-friction ball members 132 to cam the clutch shoes 70 inward, in opposition to the action of the springs 71. This will effect disengagement of the clutch shoes 70 from the clutch flange 35 of the pulley 34. The cam notches 137 may be thus caused to cooperate with the cam lugs 136 during the rotation of the rotatable clutch member 35, to cause the cam 129 upon its upper side to disengage the clutch shoes 70 from the clutch flange 35, to hold the clutch shoes 70 against further revolution. The brake-disengaging member 127 thus constitutes a clutch-disengaging member, as well.

After the clutch shoes 70 have traveled their maximum distance inward, and the brake-disengaging member 127 has been raised to the highest point possible, further pressure on the lever 128 in the same direction, toward the dotted-line position of Fig. 2, will result in forcing the annulus 133 downward to a small extent, in opposition to the force resiliently exerted at this time by the pins 134. When the annulus 133 is thus cammed downward to its lower position, following upon the upward movement of the brake-disengaging member 127, its lower face is forced into braking engagement with a suitable brake lining 140, provided upon the upper face of the annular brake disc 138.

As hereinafter more fully described, the washing or degreasing operation is performed during the rotation of the cylinders 17. After this operation has been completed, and while the cylinders 17 are still rotating, the solvent is drained off by opening a suitable drain plug 91, in the bottom wall 4. The time has now arrived to actuate the handle 128 in the opposite direction, from the dotted-line position toward the full-line position of Fig. 2, in order to effect extraction, by centrifugal action, of the solvent still remaining in the goods after the draining of the solvent.

When the hand-lever 128 is thus manipulated from the dotted-line toward the full-line position of Fig. 2, the brake-disengaging member 127 will be actuated counterclockwise. The cam lugs 136 will ride down on the cam notches 137, which will permit the brake-disengaging member 127 to become lowered at the same time that it is actuated counter-clockwise. The springs 71 will then thrust the ball members 132 outward against the beveled flange 129, to actuate the clutch shoes 70 into clutching engagement with the flange 35 of the driving pulley 34, as illustrated in Fig. 5. At the same time, the annulus 133 will be actuated to its upper position, in response to the resilient action of the metal pins 134, thereby to disengage the brake lining 140 on the brake disc 138.

In operation, let it be assumed that the motor 41 is disconnected from the line. The cylinders

17 may be loaded, through the doors 27 in their front open ends. To this end, the casing 46, with the cylinders 17 carried thereby, is first revolved about its vertical axis through a fractional turn, until the door 27 of one of the cylinders 17 becomes alined with the casing-door opening 14. This door 27 is then detached from its cylinder and removed through the door opening 14. That cylinder is then loaded with skins, hides, laundry, or the like. The casing 46 is then revolved through 180 degrees further, or until the other cylinder door 27 becomes alined with the casing-door opening 14. This other cylinder is then similarly loaded.

The casing 1 is then filled to the desired level with the solvent or other liquids that are to be used for the purpose of degreasing the hides or skins, or washing the laundry, or otherwise treating the contents of the cylinders 17. These liquids may be admitted through an inlet pipe 30, air being at the same time exhausted through an outlet pipe 31. The machine is now ready for operation. All that is necessary is to connect the motor 41 to the line. This effected, the motor rotates the pulley 34 and the bevel gear 36 that is fixed thereto.

Three different operations will be described, depending upon whether the lever 128 occupies the normal dotted-line, ineffective position, or the full-line effective position of Fig. 2, or a position in between (not shown). The pulley 34 and the bevel gear 36 will be assumed to be continuously driven from the motor 41 in all three positions of the lever 128.

When the lever 128 occupies the normal dotted-line position of Fig. 2, the brake-disengaging member 127 occupies its upper position, in which the clutch shoes 70 are disengaged from the flange 35, so that the clutch is ineffective, and the annulus 133 its lower position, in which it engages the brake disc 138. The cylinders 17 are therefore free to rotate about the axis of the horizontally disposed cylinder-carrying shaft 20; and the brake disc 138, in this normal position, prevents their revolution, with their carrier casing 46, about the vertically disposed axis of the carrier casing 46. The normal dotted-line position may therefore be termed the cylinder-rotation position, because the drive of the cylinders from the driven clutch member 35, when the lever 128 occupies this position, is constituted of a pure rotation about the horizontal axis. The full-line position may similarly be termed the cylinder-revolution position, because the drive of the cylinders from the clutch members 35 and 70, when the lever 128 occupies this position, is a revolution of the cylinders about the vertical axis. In the intermediate position (not shown) of this lever 128, the connection of the driven cylinders 17 to the driven clutch member 35 is such that a combined movement of rotation about the horizontal axis and revolution about the vertical axis is imparted to the cylinders.

Referring first to the operation that takes place when the lever 128 occupies the dotted-line, or rotation, position of Fig. 2, in this normal position, the brake is effective to prevent revolution of the carrier 46 and the cylinders 17 carried thereby, and the clutch is ineffective. The rotation of the bevel gear 36 is converted into rotation of the bevel gear 75 that meshes therewith, and of the horizontally disposed shaft 69 upon which the bevel gear 75 is mounted. The resulting rotation of the sprocket wheel 73 is communicated to the sprocket chain 77, and

this effects rotation of the sprocket driving wheel 76. The rotation of the sprocket wheel 76 is communicated to the shaft 20 and to the cylinders 17 carried thereby. In this dotted-line position of the lever 128, therefore, the drive from the pulley 34, the bevel gears 36 and 75, the sprocket wheels 73 and 76, and the sprocket chain 77 is transmitted to the shaft 20 to rotate the cylinders 17, with the horizontally disposed shaft 20 to which they are secured, in unison about the axis of this shaft 20, but they are at this time prevented from revolving about the vertical axis. The cylinders 17 become thus rotated about their horizontal axis at a time when they are braked against revolution about the vertical axis.

This rotation of the cylinders results in tumbling or agitating the laundry, hides or skins in the said solvent fluids, which may effect the washing of laundry, or the degreasing of hides or skins, or other desired treatment. It is desirable, for such purposes, during the rotation of the cylinders 17, to reverse their direction of rotation at the end, say, of each six complete rotations. This reversal of the direction of rotation of the cylinders tends to spread out their contents, thus preventing bunching or snarling thereof.

This reversal may be effected automatically by mechanism that is not illustrated, because well known; this mechanism may, for example, comprise an automatically operating switch for controlling the motor 41 under the control of a double-acting main switch that is closed when the lever 128 occupies its dotted-line position.

For the purpose of extracting, though other uses are also contemplated, the invention provides also for transmitting the drive from the clutch flange 35 of the pulley 34 to the gear casing 46, thus to revolve the casing 46 and the cylinders 17 in unison about the vertical axis of the casing 1.

When the lever 128 occupies its full-line, or revolution, position of Fig. 2, it may close another main switch (not shown) for effecting the operation of the motor 41 in the same direction throughout, without reversal. At this time, the brake-disengaging member 127 occupies its lower position, to permit the clutch shoes 70 to engage the clutch flange 35, as illustrated in Fig. 5; and the annulus 133 occupies its upper position, out of engagement with the revolution-preventing brake disc 138. The brake disc 138 is therefore released, or rendered ineffective, rendering the gear casing 46, with the cylinders 17 carried thereby, free to revolve about its vertical axis. Assuming the clutch to be fully effective at this time, without slip, the drive will be transmitted from the flange 35 of the pulley 34 directly to the clutch shoes 70. The consequent rotation of these clutch shoes 70 will effect revolution, about the said vertical axis, of the shaft 69 and of the lugs 119 on which it is mounted. This rotation of the lugs 119, in its turn, is communicated to the brake plate 47; and since the brake plate 47 is fixed to the gear housing 46 by the key 104, the housing 46 becomes revolved about the vertical axis, also. In this position of the lever 128, therefore, the drive is communicated directly from the flange 35 of the pulley 34, through the clutch shoes 70, solely to the gear casing 46 and the parts carried thereby, the bevel gears 36 and 75 acting at this time as though they were rigidly locked together to revolve as a unit about

the vertical axis, without relative rotation, and without the bevel gear 75 turning on its own axis. Under these conditions, the casing 46, together with the cylinders 17, and the other parts carried thereby, including the sprocket wheel 73, the cross-shaft 69, the clutch shoes 70 mounted thereon, and the brake plate 47, will revolve as a unit about the vertical axis, in the same direction throughout, without any rotation of the cylinders 17 about their horizontal axis.

It is now in order to consider what takes place at an intermediate time, after the lever 128 has been actuated out of its dotted-line position, but before the pure revolution before described takes place. For purposes of clarity of explanation, let it first be assumed that the handle 128 is maintained in an intermediate position (not shown) between the full-line and the dotted-line positions of Fig. 2. In this intermediate position, both the clutch and the brake are ineffective; the clutch shoes 70 do not effectively engage the flange 35, and the annulus 133 does not effectively engage the brake disc 138.

Because the clutch is ineffective, the cylinders 17 will still be rotated about their horizontal axis from the driven clutch member 34 through the bevel gears 36 and 75, the sprocket gear 73, the sprocket chain 71 and the sprocket gear 76. The inertia of the cylinders 17 with their loads, however, will tend to oppose the rotation of the cylinders 17 about their horizontally disposed axis. There will therefore be a tendency for the gears 36 and 75 to become locked against relative rotation to some extent. This tendency will not now be opposed, however, because the brake is likewise ineffective. There will consequently result a part rotation of the bevel gear 75 about its own axis from the bevel gear 36, and a part revolution of these bevel gears 36 and 75 as a unit about the vertical axis. As a consequence, there will take place a combined rotation of the cylinders 17 about their horizontal axis and revolution of the cylinders about the vertical axis, this combined rotation and revolution being both effected from the rotation of the bevel gear 36 alone, under drive from the motor 41, and without any engagement of the clutch shoes 70 against the clutch flange 35, and resulting solely from the inertia of the cylinders 17 and their loads.

During this combined rotation of the cylinders about the horizontal axis and revolution about the vertical axis, a gyroscopic effect is introduced that enables the contents of the cylinders to become automatically redistributed. Even though the loads on the two cylinders be unequal, therefore, they will so re-arrange themselves as to cause the cylinders and their loads to become very evenly balanced. This balance prevents uneven centrifugal stress from straining or damaging the machine during the extracting cycle.

At first, the speed of rotation of the cylinders about their horizontal axis will be large, and their speed of revolution about the vertical axis small. The speed of revolution, however, will gradually increase and that of rotation will gradually decrease. When the speed of revolution becomes sufficiently great, the lever 128 may be actuated from the intermediately disposed position (not shown) to the full-line position of Fig. 2. The clutch shoes 70 will thus be caused to grip against the clutch flange 35 at a time when they are already revolving about the vertical axis at a speed more or less approaching the speed of the clutch flange 35 itself. The clutch shoes 70 will there-

fore effect their clutching engagement against the clutch flange 35 with a minimum of shock and jar. From that time on, moreover, the clutch shoes 70 will assure pure revolution of the cylinders 17 and their loads about the vertical axis, and without any further rotation of the cylinders about their horizontal axis. The rotation of the cylinders 17 around the horizontal axis is thereafter completely stopped, and the sole motion is a revolution about the vertical axis. This condition will obtain as long as the clutch remains effective.

The above description has been upon the supposition that the lever 128 is maintained in its intermediately disposed position (not shown), following upon the completion of the washing or degreasing cycle, until the machine picks up speed. In actual practice, it is not necessary that the lever 128 be held in the intermediately disposed position. It may be actuated directly from the dotted-line to the full-line position of Fig. 2, and the same effect will take place.

This is because, upon the actuation of the lever 128 from the dotted-line toward the full-line position of Fig. 2, the brake 138 releases before the clutch shoes 70 become effective. Even though the clutch lever 128 be actuated directly from the dotted-line position to the full-line position of Fig. 2, therefore, there will be a brief interval of time following upon the release of the brake, and before the clutch shoes become effective, during which the brake and the clutch are both ineffective, and during which the combined rotation and revolution of the cylinders 17 takes place under drive from the motor, in the same manner as before described. Because of the existence of this brief period of time subsequent to the pure rotation of the cylinders and prior to their pure revolution, there is the same tendency as before described to reduce shock and jar.

Such shock and jar as might still be introduced by too early engagement of the clutch shoes 70 with the clutch flange 35, moreover, may be further minimized by suitable adjustment of the tension of the springs 71, and of the degree of inward and outward movement of the clutch shoes 70, to ensure that the clutch shoes 70 shall not grip too firmly to start out with against the clutch flange 35, but shall grip rather with a slip action until after a predetermined time delay. Further rotation of the cylinders 17 about their horizontal axis may thus be prevented at any desired time, during the combined rotation and revolution of the cylinders, after the brake has been rendered ineffective.

Owing to the before-described inertia of the cylinders 17 and the loads contained therein, the clutch shoes 70 will not immediately clutch positively against the flange 35 as soon as they engage this flange, but they will slip to some extent. Owing to this slip, the cylinders 17 will continue to rotate to some extent about the axis of the horizontal shaft 20 at the same time that they revolve about the vertical axis, in the same way as already explained. The rate of slippage gradually decreases until, finally, the clutch shoes 70, under the action of the springs 71, become enabled to grip the clutch flange 35 positively with sufficient force. Thereafter, the springs 71 will maintain the clutch shoes 70 effective. From that time on, therefore, there will be no further rotation of the cylinders 17 about the axis of the horizontal shaft 20, but the entire motion of the cylinders 17 will be a revolution about the vertical axis.

To adjust the time delay introduced by this slippage of the clutch from the moment that the clutch shoes 70 engage the clutch flange 35 until the cylinders cease rotating about their horizontal axis, threadedly adjustable stops 93 may be provided at the upper ends of the lugs 119, as illustrated more particularly in Figs. 5 and 6. These stops may engage the inner faces of the respective clutch shoes 70 to prevent their inward movement beyond the extent desired. Unauthorized or accidental adjustment of the stops 93 may be prevented by means of check nuts 95. The positions of adjustment of these stops 93, of course, will determine the dotted-line position of the hand lever 128, shown in Fig. 2; they will also ensure that the tension on the springs 71 shall be such as to provide the proper amount of tension and compression of the springs 71 for smooth operation of the clutch in changing from the rotation of the cylinders to their revolution. The presence of the stops 93, furthermore, makes it possible to adjust the lever 128 to its dotted-line position without fear of causing damage to the springs 71 or other parts of the machine, as by imposing undue strain upon the springs 71, or upon the brake disc 38. The last-named safety feature also ensures proper adjustment of the brake disc 138 without the necessity of re-adjusting the bolts 139 as the machine continues in use. The stops 93 may be readjusted as occasion demands, so as to prevent excess slippage of the clutch, such as might be introduced by wear of the clutch parts and their lining.

To the attainment of similar ends, the anti-friction ball members 132 may be rendered adjustable on their hubs 131, as by means of threads 96, and they may be locked in adjusted position in any desired way, as by means of set screws 97, shown in Fig. 2. The positions of adjustment of the ball members 132, like the positions of the stops 93, control the degree of inward movement of the clutch shoes 70, thereby likewise controlling the time of slip of the clutch shoes 70 against the clutch flange 35.

This time of slip may be adjusted to a value as low as a few seconds, or to a value as high as nearly a minute or more. Too short a time of slip, as before explained, introduces strain and jar, but too large a time involves unnecessary time lost in the operation of the machine. A total time delay of about 21 seconds has been found, in practice, to be very suitable in most cases, but this may often be effectively increased up to about 45 seconds.

When the cylinders 17 have been revolved sufficiently about the vertical axis to complete the extracting cycle, the hand lever 128 may finally be returned to its normal dotted-line position once more. This restores the brake-disengaging member 127 to its upper position, and the annulus 133 to its lower position. The clutch shoes 70, therefore, become again disengaged from the clutch flange 35, and the annulus 133 becomes again actuated into engagement with the brake lining 140 on the brake disc 138. The revolution of the gear casing 46, with the cylinder 17 and the other parts carried thereby, will thereupon become first retarded, and then ultimately stopped. Meantime, owing to continued rotation of the pulley 34 by the belt 44, the drive becomes again automatically transmitted from the bevel gear 36 to the bevel gear 75 and thence, by the sprocket-and-chain mechanism, to the shaft 20, thus restoring the 75

previously described rotation of the cylinders 17 about the horizontally disposed axis of the shaft 20.

For a time, therefore, there will again be a combined rotation of the cylinders about their horizontal axis and revolution about the vertical axis. This results in tumbling the clothes still further. This is advantageous, because the goods in the cylinders become opened out thereby, permitting them to fall away from the doors 21, against which they have been pressed by centrifugal action during the extracting cycle, when the cylinders were revolving about the vertical axis. Unloading of the goods in the cylinders becomes thus facilitated.

The revolution of the cylinders 17 about their vertical axis should be stopped, at the completion of the extracting cycle, in such position as to register or align the doors 21 of the cylinders 17 with aligned inlet and outlet air pipes 10. Hot air under pressure may then be blown into the cylinders through these doors 21, while the cylinders are still being rotated about their horizontal axis. Because the contents of the cylinders have already fallen away from the doors 21, the hot air becomes enabled to penetrate into the clothes in the cylinders 17. Most of the residual solvent remaining in the goods after the draining is removed from the goods during the extraction cycle; the hot-air blast removes the remainder, in order to complete the drying.

This final combined rotating-and-revolving movement of the cylinders, subsequent to the extracting operation, may be effected at a time 35 when the power from the motor 41 is shut off, and wholly by the inertia of the moving cylinders and their loads; the motor may be disconnected from the line. Though no power is at this time obtained from the motor, the machine 40 will continue its combined rotation and revolution of the cylinders by its own inertia if the motor switch is opened while the cylinders are still revolving. During the continued revolution of the machine about the vertical axis by its 45 inertia, there is introduced also a rotation of the cylinders about their horizontal axis, caused by relative movement of the gears 36 and 75, as before described. The gears 36 and 75 lock to some extent, to permit revolution of the cylinders, but they rotate also with respect to each 50 other to some extent, to permit rotation of the cylinders.

A machine is thus provided by the present invention that positively, and without fail, will perform the functions demanded of it, and exactly at the times when so demanded. When the hand lever 128 occupies its extreme normal dotted-line position, the motion of the cylinders 17 will be a pure rotation about their horizontal axis, revolution about the vertical axis being, at this time, prevented by the annulus 133 engaging the brake lining 140 upon the brake disc 138. Upon the actuation of the lever 128 to its extreme full-line position, a suitable time interval will ensue, 65 the length of which may be adjusted, during which there will be combined rotation of the cylinders about the horizontal axis and revolution of the cylinders as a unit about the vertical axis. The speed of revolution about the vertical axis gradually increases, and the rotation about the horizontal axis gradually decreases, until the speed of rotation about the horizontal axis stops altogether, at a time determined by the adjustment. The sole motion thereafter is a pure revolution only of the cylinders about their vertical

axis as a unit, without horizontal rotation. By actuating the lever 128 to an intermediate position, where such may be desired, it is possible also to obtain combined rotation of the cylinders about the horizontal axis and revolution about the vertical axis, until the machine runs down by its inertia.

Modifications will occur to persons skilled in the art, and all such are considered to fall within the spirit and scope of the invention, as defined in the appended claims.

What is claimed is:

1. A machine of the character described having, in combination, a plurality of substantially axially aligned cylinders rotatable about their axis, a brake for preventing the revolution of the cylinders during their rotation, means for simultaneously rotating the cylinders about their axis and revolving the cylinders about another axis between the cylinders, and means operable after the release of the brake for preventing the rotation of the cylinders during their revolution.

2. A machine of the character described having, in combination, a plurality of substantially axially aligned cylinders, means for simultaneously rotating the cylinders about their axis and revolving the cylinders about another axis between the cylinders, and means for preventing the rotation of the cylinders during their revolution.

3. A machine of the character described having, in combination, a plurality of substantially axially aligned cylinders rotatable about their axis, a brake for preventing the revolution of the cylinders during their rotation, and means for first simultaneously rotating the cylinders about their axis and revolving the cylinders about another axis between the cylinders and then effecting revolution of the cylinders without rotation.

4. A machine of the character described having, in combination, a driven clutch member, a cooperating clutch member that may be actuated into engagement with the driven clutch member so as to be actuated therewith, a shaft, bearings in which the shaft is journaled with its ends projecting beyond the respective ends of the bearings, two cylinders each having end walls, the cylinders being carried by the respective ends of the shaft each at one of the end walls, means controlled by the driven clutch member at a time when the cooperating clutch member is disengaged therefrom for rotating the shaft, the said means comprising a planetary gear drive connected to the driven clutch member and including a gear, a sprocket driven by the gear, and a sprocket chain mounted over the sprocket and connected to the shaft between the bearings, means for actuating the cooperating clutch member into clutching engagement with the driven clutch member at any desired time, means connecting the shaft to the cooperating clutch member to revolve the shaft, the bearings and the cylinders as a unit from the cooperating clutch member when the cooperating clutch member is in engagement with the driven clutch member, and means for preventing rotation of the shaft during its revolution.

5. A machine of the character described having, in combination, a casing, a pair of combination tumbler-and-extractor cylinders in the casing, a shaft connecting the cylinders together in fixed axially spaced relation for rotation in unison about a horizontal axis, a shaft-carrier upstanding along the vertical axis of the casing between the cylinders and rotatably mounted in the casing to revolve the shaft and the cylinders

5 in unison about the vertical axis, means for rotating the shaft, means for rotating the carrier, and means for preventing the rotation of the shaft at any desired time during the rotation of the carrier.

6. A machine of the character described having, in combination, a casing, a pair of combination tumbler-and-extractor cylinders in the casing, a shaft connecting the cylinders together in fixed axially spaced relation for rotation in unison about a horizontal axis, a shaft-carrier upstanding along the vertical axis of the casing between the cylinders and rotatably mounted in the casing to revolve the shaft and the cylinders in unison about the vertical axis, a rotatable clutch member, a cooperating clutch member that may be actuated into clutching engagement with the rotatable clutch member so as to be rotated therewith, means controlled by the rotatable clutch member at a time when the cooperating clutch member is disengaged therefrom for rotating the shaft, means for actuating the cooperating clutch member into clutching engagement with the rotatable clutch member at any desired time, and means connecting the carrier to the cooperating clutch member to rotate the carrier.

7. A machine of the character described having, in combination, a cylinder rotatable about its axis to tumble its contents and revolvable about an axis external to the cylinder to extract liquid from the tumbled contents, means operable to prevent revolution of the cylinder during its rotation, means operable when the preventing means is ineffective for simultaneously rotating the cylinder about its axis and revolving the cylinder about the external axis, means operable during the simultaneous rotation and revolution of the cylinder for preventing the rotation of the cylinder to effect revolution of the cylinder without rotation thereof, and means for controlling the time at which the rotation of the cylinder is prevented during the combined rotation and revolution of the cylinder.

8. A machine of the character described having, in combination, a cylinder rotatable about its axis to tumble its contents and revolvable about an axis external to the cylinder to extract liquid from the tumbled contents, a brake for preventing revolution of the cylinder during its rotation, means operable upon release of the brake for simultaneously rotating the cylinder about its axis and revolving the cylinder about the external axis, a normally ineffective clutch that may be rendered effective during the combined rotation and revolution of the cylinder to stop its rotation, thereby to effect revolution of the cylinder without rotating it, means for rendering the clutch effective, and means for controlling the time at which the clutch becomes effective.

9. A machine of the character described having, in combination, a plurality of cylinders, means for simultaneously rotating the cylinders about their axes and revolving the cylinders as a unit about another axis, and means for preventing rotation of the cylinders at any desired time during their simultaneous rotation and revolution.

10. A machine of the character described having, in combination, a plurality of substantially axially aligned cylinders, means for simultaneously rotating the cylinders about their axis and revolving the cylinders as a unit about another axis between the cylinders, and means for preventing

rotation of the cylinders at any desired time during their simultaneous rotation and revolution.

11. A machine of the character described having, in combination, a shaft, a bearing in which the shaft is journaled and beyond which the ends of the shaft extend, two cylinders each having end walls, the cylinders being carried by the respective ends of the shaft, each at one of the end walls, means for simultaneously rotating the shaft and revolving the cylinders and the shaft as a unit about an axis at an angle to the axis of the shaft, and means for preventing rotation of the shaft at any desired time during the simultaneous rotation of the shaft and revolution of the cylinders and the shaft as a unit.

12. A machine of the character described having, in combination, a plurality of substantially axially aligned cylinders rotatable about their axis to tumble their contents and revolvable about an axis externally disposed between the cylinders at right angles to their axis to extract liquid from the tumbled contents, means operable to prevent revolution of the cylinders during their rotation, means operable when the preventing means is ineffective for simultaneously rotating the cylinders about their axis and revolving the cylinders about the external axis, and means operable during the simultaneous rotation and revolution of the cylinders for preventing the rotation of the cylinders at any desired time.

13. A machine of the character described having, in combination, a plurality of substantially axially aligned cylinders rotatable about their axis to tumble their contents and revolvable about an axis between the cylinders at right angles to their axis to extract liquid from the tumbled contents, a brake for preventing revolution of the cylinders during their rotation, means operable upon release of the brake for simultaneously rotating the cylinders about their axis and revolving the cylinders about the external axis, a normally ineffective clutch that may be rendered effective during the combined rotation and revolution of the cylinders to stop their rotation, thereby to effect revolution of the cylinders without rotating them, means for rendering the clutch effective, and means for controlling the time at which the clutch becomes effective.

14. A machine of the character having, in combination, a normally ineffective clutch comprising a rotatable clutch member and a cooperating clutch member; means for continuously rotating the rotatable clutch member; a cylinder; a carrier rotatable with the cooperating clutch member; the cylinder being carried by the carrier so as to revolve during the rotation of the carrier about an axis at right angles to the axis of the cylinder; means connecting the cylinder to the rotatable clutch member to rotate the cylinder about its axis and to rotate the carrier to effect revolution of the cylinder about the said axis at right angles to the axis of the cylinder; means effective normally, when the clutch is ineffective, to prevent the rotation of the carrier, whereby, normally, when the clutch is ineffective, the cylinder is rotated about its axis from the rotatable clutch member but without being revolved about the axis at right angles to the axis of the cylinder; means for rendering the preventing means ineffective, whereupon a combined rotation about its axis and revolution about the axis at right angles to its axis becomes imparted to the cylinder from the rotatable clutch member; normally ineffective means operable when effective to render the clutch effective and thereafter to main-

tain the clutch effective; means connecting the carrier to the cooperating clutch member to rotate the carrier from the cooperating clutch member when the clutch is effective; and means operable during the said combined rotation and revolution of the cylinder to prevent its further rotation at any desired time after the revolution-preventing means has been rendered ineffective, whereby, thereafter, during the effectiveness of the means for rendering and maintaining the clutch effective, the cylinder is revolved about the axis at right angles to its axis but without being rotated about its axis.

15. A machine of the character described having, in combination, a normally ineffective clutch comprising a clutch member rotatable about a first axis and a cooperating clutch member; means for continuously rotating the rotatable clutch member about the first axis; a bevel gear rotatable with the rotatable clutch member about the first axis; a bevel gear meshing with the first-named bevel gear and rotatable about a second axis; the second-named bevel gear being revolvable about the first axis in response to the rotation of the first-named bevel gear when the second-named bevel gear is prevented from rotating about the second axis; the cooperating clutch member being non-rotatable with respect to the second-named bevel gear but being rotatable with the second-named bevel gear about the first axis; a cylinder the axis of which is at right angles to the first axis; a shaft coaxial with the cylinder and upon which the cylinder is mounted; a carrier rotatable with the cooperating clutch member; the shaft and the cylinder mounted thereon being carried by the carrier so as to revolve during the rotation of the carrier about the first axis; means connecting the shaft to the second-named bevel gear to rotate the shaft and the cylinder about the axis of the cylinder and to rotate the carrier to effect revolution of the shaft and the cylinder about the first axis; means effective normally, when the clutch is ineffective, to hold the second-named bevel gear and the cooperating clutch member, together with the carrier, against rotation about the first axis during the rotation of the shaft, whereby, normally, when the clutch is ineffective, the cylinder is rotated about its axis from the rotatable clutch member but without being revolved about the first axis; means for rendering the holding means ineffective, whereupon the second-named bevel gear becomes rotatable about the second axis in response to the rotation of the first-named bevel gear about the first axis to effect a combined rotation of the cylinder about its axis and revolution thereof about the first axis from the rotatable clutch member; normally ineffective means operable when effective to render the clutch effective and thereafter to maintain the clutch effective; means connecting the cylinder to the cooperating clutch member to revolve the cylinder about the first axis from the cooperating clutch member when the clutch is effective; and means operable during the said combined rotation and revolution of the cylinder to revolve the cylinder and the shaft upon which it is mounted as a unit with the second-named bevel gear about the first axis, thereby to prevent further rotation of the cylinder at any desired time after the holding means has been rendered ineffective, whereby, thereafter, during the effectiveness of the means for rendering and maintaining the clutch effective, the cylinder is re-

volved about the first axis but without being rotated about its axis.

16. A machine of the character described having, in combination, a casing, a carrier revoluble in the casing about a vertical axis, a shaft horizontally disposed on the carrier in the casing, two cylinders in the casing each having two end walls one of which is open, the cylinders being fixed to the respective ends of the shaft with their axes horizontally aligned with the axis of the shaft, means for rotating the cylinders about their aligned axes and for rotating the carrier about the vertical axis to revolve the cylinders in the casing, a brake for preventing rotation of the carrier to effect rotation of the cylinders about their aligned axes without revolution of the cylinders about the vertical axis, means for releasing the brake to effect a combined rotation of the cylinders about their aligned axes and revolution about the vertical axis, and means operable during the said combined rotation and revolution of the cylinders for preventing their further rotation at any desired time after the release of the brake, whereby the cylinders will thereafter revolve without rotation.

17. A machine of the character described having, in combination, a driven clutch member, a cooperating clutch member that may be actuated into engagement with the driven clutch member

so as to be actuated therewith, a shaft, two cylinders each having end walls, the cylinders being carried by the respective ends of the shaft each at one of the end walls, means controlled by the driven clutch member at a time when the cooperating clutch member is disengaged therefrom for rotating the shaft, means for actuating the cooperating clutch member into clutching engagement with the driven clutch member at any desired time, means connecting the shaft to the cooperating clutch member to revolve the shaft and the cylinders as a unit from the cooperating clutch member when the cooperating clutch member is in engagement with the driven clutch member, and means for preventing rotation of the shaft during its revolution.

18. A machine of the character described having, in combination, a cylinder rotatable about its axis to tumble its contents and revolvable about an axis external to the cylinder to extract liquid from the tumbled contents, means for simultaneously rotating the cylinder about its axis and revolving the cylinder about the external axis, and means for preventing rotation of the cylinder at any desired time during its simultaneous rotation and revolution.
